TOY FIGURE FOR CATS

Dorothy Childs Hogner, Goshen, Conn.

Application August 13, 1948, Serial No. 148,093

Term of patent 7 years

(Cl. D34—2)

To all whom it may concern:

Be it known that I, Dorothy C. Hogner, a citizen of the United States, residing at Goshen, in the county of Litchfield and State of Connecticut, have invented a new, original, and ornamental Design for a Toy Figure for Cats, of which the following is a specification, reference being had to the accompanying drawing, forming part thereof.

Fig. 1 is a plan view of a toy figure for cats, showing my new design.

Fig. 2 is a side view of the toy figure for cats shown in Fig. 1.

I claim:

The ornamental design for a toy figure for cats, as shown.

DOROTHY CHILDS HOGNER.
